Attorney

UNITED STATES PATENT OFFICE.

JAMES C. RUMFELT, OF MANES, MISSOURI.

ENGINE-REPAIR STAND.

Application filed December 15, 1924. Serial No. 756,073.

To all whom it may concern:

Be it known that I, JAMES C. RUMFELT, a citizen of the United States, residing at Manes, in the county of Wright and State 5 of Missouri, have invented certain new and useful Improvements in an Engine-Repair Stand, of which the following is a specification.

This invention relates to improvements 10 in repair stands and is more particularly adapted to a device for supporting an internal combustion engine after the same has been removed from the automobile in order to make the necessary repairs thereto.

15 One of the important objects of the present invention is to provide an engine repair stand of the above mentioned character, wherein means is provided for adjusting the engine supporting means to various 20 positions whereby the engine may be disposed in various positions depending upon the work to be done thereon, thus enabling the mechanic to obtain easy access to the parts of the engine requiring repair.

25 A still further object of the invention is to provide an engine repair stand of the above mentioned character, which is of a portable nature so that the same may be transported from place to place as may be 30 desired.

A still further object is to provide an engine repair stand of the above mentioned character, which is simple in construction, inexpensive, strong and durable and further 35 more adapted for the purposes for which it is designated.

Other objects and advantages of this invention will become apparent during the course of the following description.

40 In the accompanying drawings forming a part of this specification and in which like numerals designate like parts throughout the same:

Figure 1 is a side elevation of the device 45 embodying my invention showing an internal combustion engine supported thereon in normal upright position.

Figure 2 is an end elevation of the stand.

Figure 3 is a top plan view thereof.

50 Figure 4 is a fragmentary detail showing the engine supporting means disposed in a vertical plane, and

Figure 5 is a further detail showing the 55 position of the engine support when the engine is in an inverted position.

In the drawings, wherein for the purpose

of illustration is shown the preferred embodiment of my invention, the numeral 1 designates the base or platform of my improved engine repair stand and suitable ground engaging wheels 2 are associated therewith for rendering the device portable. The base or platform 1 is substantially rectangular in design. A pair of opposed standards 3 and 4 respectively are secured 60 at their lower ends on the intermediate portion of the base adjacent the respective sides thereof as illustrated at 5. The upper ends of the standards are disposed inwardly and thence upwardly as clearly illustrated 65 in Figure 2 and pivotally supported on the inner faces of the upper ends of the standards are the opposed angle iron members 6 and 7 respectively. 70

The angle iron members are pivotally supported intermediate their ends on the upper ends of the respective standards as illustrated at 8 and the top of each of the angle irons is provided with suitable openings for receiving the fastening bolts whereby an 75 internal combustion engine which has been removed from the automobile may be rigidly secured on the angle irons in the manner as clearly illustrated in Figure 1. The 80 openings provided in the top of the angle iron engine supporting members are illustrated at 9 with reference more particularly to Figure 3 of the drawings. The sides of the angle iron engine supporting members are also provided with openings adjacent the 85 ends thereof as indicated at 10. The purpose of the openings 10 in the sides of the angle irons will hereinafter be more fully described.

A pair of substantially inverted U-shaped 90 brackets 11 and 12 respectively have the intermediate portions of the crowns thereof secured to the intermediate portion of the standards 3 and 4 respectively as indicated at 13. The free ends of the arms of each of the inverted U-shaped brackets are disposed laterally and are secured to the base or platform 1 as illustrated at 14. The crown portion of each of the inverted U-shaped brackets is provided with openings 15 adjacent 95 the arms of the bracket.

A pair of elongated levers or arms 16 and 17 respectively are pivotally secured at their upper ends to the forward ends of the angle iron engine supporting members 6 and 7 100 respectively. A bolt 18 extending through the upper end of each of the levers or arms 105

110

and through the registering openings provided in the side of the adjacent angle iron member at the forward end thereof. The lower ends of the levers or arms are curved 5 as illustrated at 19 and terminate at a point above the platform 1. The levers 16 and 17 are pivotally supported intermediate their ends on the forward end of the crown portion of the inverted U-shaped brackets 10 11 and 12 respectively by means of the detachable pivot bolts 20.

With the parts arranged as shown in Figure 1 of the drawing, the internal combustion engine which is secured in a rigid position 15 on the angle iron members 6 and 7 will be supported in its normally upright position, such as it normally occupies when in the automobile. When it is desired to support the internal combustion engine in a 20 vertical position such as is clearly illustrated in Figure 4, the bolts 20 are removed and the angle iron engine supporting members 6 and 7 are adapted to swing on their pivots on the upper ends of the standards so that 25 the engine will be disposed vertically between the standards. The lower ends of the levers or arms are then adapted to be swung into positions so that the openings 21 in the lower curved ends of the levers will be in 30 engagement with the openings 15 provided in the crown portions of the inverted U-shaped brackets at the rear end thereof. Suitable fastening bolts or the like shown at 22 are then adapted to be inserted 35 through the registering openings provided in the lower ends of the levers and the rear ends of the inverted U-shaped brackets for securing the levers in a rigid position.

If it is desired to turn the internal combustion engine upside down and hold the same in such inverted position, the levers will be disposed in the position shown in Figure 5 of the drawings wherein the same will be disposed adjacent the rear ends of 45 the inverted U-shaped brackets and fastened at their intermediate portions to the crown portions of the brackets.

The provision of an engine repair stand of the above mentioned character, enables 50 an internal combustion engine to be supported in various positions so that a mechanic may have ready access thereto in order to make the necessary repairs in a simple and efficient manner.

55 The simplicity in which my improved stand is constructed enables the parts to be readily adjusted and furthermore there will be no possibility of the parts being accidentally moved out of their adjusted positions.

60 An engine repair stand of the above mentioned character, will save considerable time and labor in repairing an internal combustion engine and may be used in connection with internal combustion engines of various makes.

While I have shown the preferred embodiment of my invention, it is to be understood that various changes in the size, shape and arrangement of parts may be resorted to without departing from the spirit of the 70 invention and the scope of the appended claims.

Having thus described the invention, what I claim is:—

1. An engine repair stand comprising a 75 base, a pair of opposed standards supported at the lower ends thereon, a pair of brackets secured on said base and attached to the respective standards, a pair of angle iron engine supporting means pivotally secured intermediate their ends on the upper ends of the respective standards, and levers pivotally secured at their upper ends to the respective angle iron members and adapted for cooperation with said brackets for supporting the angle iron members in various positions. 80 85

2. An engine repair stand comprising a wheeled base, a pair of opposed standards secured at their lower ends on the intermediate portion of said base, a pair of substantially inverted U-shaped brackets secured at their lower free ends on said base and adapted to be attached to the respective standards, a pair of angle iron engine supporting members pivotally secured intermediate their ends on the upper ends of the respective standards, said angle iron engine supporting members being adapted for swinging movement between said standards, means associated with the angle iron members and cooperating with the respective brackets for holding the angle iron engine supporting members in various positions, said means comprising a pair of levers, the upper ends 105 thereof being pivotally secured to the ends of the respective angle iron members, said levers being provided with openings therein for cooperation with openings in the respective brackets, and fastening means extending 110 through said registering openings. 100

3. An engine repair stand comprising a wheeled base, a pair of opposite standards secured at their lower ends on the intermediate portion of said base, a pair of substantially inverted U-shaped brackets secured at their lower free ends on said base, the intermediate portions of the crown portions of the bracket being attached to the respective standards adjacent the upper end thereof, a pair of angle iron engine supporting members pivotally secured intermediate their ends on the upper ends of the respective standards, said angle iron engine supporting members being adapted for swinging movement between the standards, and means for holding the angle iron engine supporting members in various positions, said means comprising a pair of levers pivotally secured 115 120 125 at one end to the ends of the respective angle 130

iron members, said levers being provided with openings in the intermediate portions thereof and in their free ends, the crown portions of the respective brackets being also provided with openings adjacent the depending arms of the inverted U-shaped brackets for cooperation with the openings

in the respective levers, and fastening means extending through registering openings of the levers and the brackets.

In testimony whereof I affix my signature.

JAMES C. RUMFELT.
